CALK STRUCTURE

Daniel W. Wiggin, Yarmouth, Maine, assignor to
 The Abbott Company, Wilton, Maine, a corpora-
 tion of Maine

Application November 22, 1932, Serial No. 643,853

4 Claims. (Cl. 36—59)

My present invention relates to calk sole structures for shoes and like footwear and to a calk for such articles.

Calk soled shoes are used widely. For the most part these shoes are worn in such sports as require firm footing and freedom from the possibility of slipping. Even in normal wear, it is frequently necessary to replace calks.

Most of the calk sole structures and calks heretofore produced, particularly those of detachable nature, have been complicated and costly to install by reason of involving hand operations.

My invention contemplates a new calk structure which produces a superior sole structure as to wearing qualities and as to the attaching and detaching of the calk points. The shoe structure contemplated makes efficient production possible by machine setting operations and by rendering impossible splitting of the tubular sole member below a desired point below the inside of the sole.

As illustrative of my invention I have shown embodiments which indicate the principles involved and at the same time provide simple, effective and inexpensive structures and operations. 25 In the drawing and specification, like reference numerals are used to indicate corresponding parts.

In the drawing:

Fig. I is a partly sectional view of a shoe structure such as is involved.

Fig. II is a sectional view of the calk in place.

Fig. III is a sectional view of the tubular sole member.

Fig. IV is a side view of the calk to be used 35 therein.

Figs. V and VI are face views of the inter-engaging collar members.

Figs. VII and VIII are views of similar calk members having radially flanged engagements, 40 and

Fig. IX is a sectional view of a calk in place showing a modified sole member.

In providing such a calked sole this invention contemplates a two part calk member. One part indicated as at 1 consists of a tubular sole piece. This has a flange 2 at one end adapted to abut the outer surface of a sole S, but said flange may be otherwise formed or omitted. In Fig. IX, the tubular sole piece is formed as a blind eyelet, the 50 end thereof 2^a, when set, lying within the surface of the leather. The tubular sole member thus formed has some structural advantages.

Internally as at 4 the member 1 is threaded to receive the calk shank. At the inner end of the 55 threaded area there is a circumferentially located

shoulder 3^a to prevent the splitting of the tubular sole piece below this point during the clinching and allowing for a maximum internally threaded receiving aperture 4 for the calk. At its inner end 3, the tubular sole piece is of less thickness 60 than the threaded portion and may be tapered or flared as in Fig. III, so that the portion may be sprung or outwardly spread to clinch the member as is shown in Figs. I and II. The inner end of the tubular sole member may be scored to 65 facilitate clinching as at 1^a in Fig. IX.

The calk member consists of a point 10 having a threaded shank 11 and a flange 12. The flanges 2 and 12 will be interlocked when the calk and sole members are screwed up as shown in Fig. II. 70 The interlock may be variously effected as by projections 13 and recess 5 as in Figs. III to VI.

In Figs. VII and VIII a modified form of calk is shown in which the flange 16 of the sole member 15 has serrations 17. These engage with similar serrations 18 on the flange 19 of the calk member 20. The flanges as in the form previously described yield slightly on engagement permitting interlocking of the serrations.

The tubular sole members 1 may be set in the 80 soles S as by a standard eyeletting machine. The calks may then be screwed therein until the flanges interengage. Such calks permit efficient and practical production with a very much improved sole structure resulting. The sole member 85 may be formed like a blind eyelet and so set. In such case the calk flange supports the sole adjacent the eyelet set.

The calk points may be removed or substituted and may be given any shape or form desired 90 adding to the utility of any shoe. The points may be pyramidal as indicated in Fig. IV or conical as in Fig. VIII. The pyramidal form is convenient because a better grip for a wrench is afforded, but flattened faces may be provided in 95 any form.

Various modifications in the construction and operations of my device may obviously be resorted to without departing from the spirit of my invention if within the limits of the appended claims. 100

What I therefore claim and desire to secure by Letters Patent is:

1. In a shoe structure, a sole and calk assembly including a tubular insert comprising a sleeve having at its inner end a reduced portion 105 clinched to the inner face of the sole, a shoulder from which the reduced portion extends, said sleeve being threaded internally toward the shoulder, a flanged outer end, and a detachable calk with a threaded shank engaging said sole 110

- member and having an external flange compressibly reinforcing the insert and adjacent sole structure and serving to hold the two members in set position. 80
- 5 2. A calk sole shoe structure comprising a member inserted through the sole, an outwardly directed flange on the outer end thereof in engagement with the outer face of the sole, internally threaded to receive a calk, a shoulder at 10 the inner end of the threaded portion, the inner end of said member being outwardly tapered therefrom and deflectively clinched against the inner surface of the sole. 85
- 15 3. A calk assembly for shoe soles comprising a tubular member to be inserted through a sole, a stop formation on said member for engagement with the outer face of the sole to limit the insertion of the member, the member being of a 20 length to extend at its inner end beyond the inner face of the sole when the stop formation is engaged with the outer face of the sole, the main

portion of said member having a sufficiently thick wall to sustain the shape and permit screw threading thereof, said member being interiorly screw threaded, a shoulder adjacent the upper end of the screw threaded area, the inner portion of said member being adapted to be deflected outwardly and clinched to the inner face of the sole, being of less thickness than said member below the shoulder, and a calk having a threaded shank to be threaded into said member. 85

4. In a shoe structure, a sole and a calk member comprising a tubular insert having a flange at its outer end, said tubular insert being interiorly threaded in its outer end, the inner portion being of less thickness than the threaded end, a shoulder intermediate said threaded end and said inner portion, and said inner portion being clinched to the inner sole surface beyond said shoulder, and a calk threaded therein. 90
